UNITED STATES PATENT OFFICE.

OSCAR C. KROSHAUG, OF VOLGA, SOUTH DAKOTA.

LOCK.

1,256,910.

Specification of Letters Patent. Patented Feb. 19, 1918.

Application filed April 26, 1917. Serial No. 164,723.

To all whom it may concern:

Be it known that I, OSCAR C. KROSHAUG, a citizen of the United States, residing at Volga, in the county of Brookings and State 5 of South Dakota, have invented certain new and useful Improvements in Locks, of which the following is a specification.

This invention relates to hardware, and more particularly to locks for barn, shed, 10 garage and similar doors.

The object of the invention is to provide a quick acting, strong, simple and cheap lock of this character which is especially designed for use on large high doors for securing them both at the top and bottom and which is operable from a point within convenient reach.

With the foregoing and other objects in view, which will appear as the description 20 proceeds, the invention resides in the combination and arrangement of parts and in the details of construction hereinafter described and claimed, it being understood that changes in the precise embodiment of 25 the invention herein disclosed may be made within the scope of what is claimed without departing from the spirit of the invention.

In the accompanying drawings:—

Figure 1 is a transverse section of a building equipped with this invention looking toward the inside of the doors,

Fig. 2 is a vertical section taken on the line 2—2 of Fig. 1,

Fig. 3 is an enlarged detail view of the 35 interior of the doors showing the lock in open position.

In the embodiment illustrated, a building B is shown having a pair of double doors D D, such as are usually employed on barns, 40 stables and the like.

The lock constituting this invention comprises a pair of locking bolts or rods 1 and 2 which are pivotally connected at their inner ends with the ends of a lever 3 which is fulcrumed intermediately of its ends on a substantially inverted U-shaped support 4 mounted on one of the doors D and which is here shown disposed on the inner face thereof with the terminals of the legs thereof extended laterally outward and apertured to form attaching means. This lever 3 has a handle 5 as shown clearly in Fig. 2 to afford a convenient gripping member for actuating the lever to throw the rods into and out of locking position, it being obvious that when these rods are in longitudinal alinement they

will be projected into locking position and when they are disposed out of alinement and in parallel planes as shown in Fig. 3, they will be in released or retracted position and 60 which release is accomplished by swinging the lever 3 into the position shown in dotted lines in Fig. 3.

Guides 6 and 7 in the form of keepers are shown arranged at the upper and lower ends 65 of the door respectively and through which the locking ends of the rods are designed to pass and be guided preventing their accidental disengagement from the door. A keeper 8 is shown arranged on the upper 70 cross bar 9 of the door frame in alinement with the keeper 6 when the door is in closed position as is shown clearly in Fig. 1, and into which the end of rod 1 is designed to project for locking the door at its upper end. 75 The door sill S is shown provided with a socket 10 in its upper face adjacent the outer face of the lower end of the door D which carries the lock and which is designed to receive the lower end of rod 2 when the lock 80 is in operative position as is shown clearly in Fig. 2.

It is to be understood that while the keeper is shown on the outer face of the cross bar 9 at the top of this door, and the 85 socket 10 in the sill thereof, that this construction may be varied according to the manner in which the door is mounted, it being understood that when the door is set flush with the bar 9 as shown at the top of 90 Fig. 2 that the keeper will be employed to receive the end of rod 1 when projected. When it is set inward beyond the outer face of the door frame as shown at the bottom of Fig. 2 the socket may be employed 95 to receive the rod.

It is also to be understood that while the member 4 is shown for supporting the lever 3, the object being to space the lever a sufficient distance from the face of the door to 100 permit its free turning, and the movement of the rods without engagement with the door.

The handle member 5 of lever 3 is constructed of resilient metal and the downward turned end 5' thereof normally projects inward beyond rod 2 so that when the lever is swung into operative locking position and the handle arranged over rod 2 said end 5' will bear against rod 2 and lock the lever 110 against accidental turning thereby securely holding the doors in closed position.

In the operation of this lock, the doors being shown in the position indicated in Figs. 1 and 2, which is a locked operative position, and it is desired to open the door, the handle 5 is gripped and moved upwardly thereby swinging the lever on its fulcrum and lowering rod 1 and elevating rod 2 thereby retracting their outer ends from engagement with the keeper 8 and socket 10 respectively, and thus unlocking the door. To lock the door, the operation is reversed, the handle being moved downwardly, thereby swinging the lever upwardly and bringing rods 1 and 2 into longitudinal alignment causing their free ends to project into locking engagement with keeper 8 and socket 10.

While this lock is shown and is preferably used on the inside of a door, it is obvious that it may be used on the outside thereof and the handle 5 is shown provided with a notch 5" in its terminal which engages rod 2 when sprung into operative position thereby securely holding the lever against accidental movement such as would be likely to disengage the locking rods.

The structure shown is very simple, quick acting and strong, rendering it particularly adapted for the purpose for which it is designed and by making rod 2 shorter than rod 1, the actuating lever may be positioned at a point convenient for use by an ordinary person without any unnecessary reaching up.

From the foregoing description, taken in connection with the accompanying drawings, the advantages of the construction and of the method of operation will be readily apparent to those skilled in the art to which the invention appertains and while I have described the device which I now consider

to be the best embodiment thereof, I desire to have it understood that the device shown is merely illustrative and that such changes may be made as are within the scope of the claimed invention.

I claim:-

The combination with a door frame having rod receiving sockets; of a door having rod guides arranged at its upper and lower ends on one face thereof and in longitudinal alignment with each other and with said sockets when the door is closed, a pair of locking rods mounted to slide in said guides, a substantially inverted U-shaped support having a rectilinear cross bar and the terminals of its legs bent laterally out and apertured for attachment to the door, a lever in the form of a metal bar fulcrumed intermediately of its ends on the cross bar of said support and pivotally connected at opposite sides of its fulcrum on the inner ends of said rods, said lever having a substantially inverted U-shaped longitudinal extension at one end offset laterally from the body of the lever and rigidly secured at the end of one leg thereto, to form a handle therefor, said handle having its free leg turned inwardly and extended into a plane beyond that of the lever body and having a notch in its terminal for locking engagement with the rod on which it is superposed when the parts are in operative position and whereby the rods are held against accidental release from the socket.

In testimony whereof I affix my signature in presence of two witnesses.

OSCAR C. KROSLAUG.
